UNITED STATES PATENT OFFICE.

STANLY TANSKI, OF EAST VANDERGRIFT, PENNSYLVANIA.

LOCK.

1,409,429.

Specification of Letters Patent. Patented Mar. 14, 1922.

Application filed December 29, 1920. Serial No. 433,793.

To all whom it may concern:

Be it known that I, STANLY TANSKI, citizen of the United States, residing at East Vandergrift, in the county of Westmoreland 5 and State of Pennsylvania, have invented certain new and useful Improvements in Locks, of which the following is a specification.

This invention relates to door locks, and 10 it has for an object to provide a novel form of lock, of considerable strength, and in which a simple and inexpensive means is employed to render the picking thereof difficult, the invention being designed more particularly for application to sliding doors, 15 such as barn doors or the like.

For further comprehension of the invention, and of the objects and advantages thereof, reference will be had to the following description and accompanying drawings, 20 and to the appended claims in which the various novel features of the invention are more particularly set forth.

Fig. 1 of the drawings is a perspective view of a lock constructed according to the invention, showing a portion of a door in which it is fixed.

Fig. 2 is a perspective view showing a portion of the door with the keeper in position 30 thereon.

Fig. 3 is a face view of the lock with the face plate removed and certain of the interior parts shown in vertical section.

Fig. 4 is a transverse vertical section on 35 the line 4—4 of Fig. 3.

Fig. 5 is a similar view to Fig. 3, but showing a modified construction of the lock.

As here shown my improved lock comprises a casing 10 of generally rectangular 10 shape and formed at upper and lower ends with holes 11 for the insertion of screws 12 whereby it may be secured to the sliding door 13, the casing being set into the edge 45 of the door with its outer face flush with said edge, and being here shown as of a width equal to the thickness of the door, with its sides flush with the opposite faces of the latter. Upon the outer face of the casing is a removable face plate 14 secured in 50 place by screws 15.

Mounted in the casing 10, to be slidable in a direction transversely of the door 13, is a bolt 17 which may be of vertically elongated rectangular cross section and is of a 55 length somewhat greater than the width of the casing 10, being accommodated in groove

18 cut in the front face of the casing from side to side thereof and being held against displacement by the face plate 14. This bolt 17 has a knob or handle 20 on the end 60 thereof which projects at the outer face of the door.

Arranged to slide vertically in the casing 10 and engage and hold the bolt 17, is a tumbler bar 21 which is held against outward 65 displacement by the face-plate 14 and which extends vertically across the face of the bolt through a widened groove 22 in the latter, the lower and upper portions being widened to project under and over the bolt, the widened upper portion forming a hook or lug 21' which is adapted to engage in a notch 23 in the bolt to lock the latter.

The tumbler bar 21 is moved vertically, to bring the lug 21' into or out of engagement 75 with the notch 22, by the following means. Formed in the lower portion of the tumbler bar is a circular aperture 24 which registers with, but is eccentrically disposed with relation to, a larger aperture or boring 25 80 which extends inwardly from the outer edge wall of the casing 10 to the groove 26, in which the tumbler bar is located, this groove being of slightly greater length than the tumbler bar to permit vertical movement of 85 the latter. Rotatably mounted in the outer end of this boring 25 is a disk 27 having a key-hole 28 therein and being provided on its periphery with gear teeth 29. As here shown the disk 27 may be held in place by a 90 plate 30 secured in place by screws 31, a widened recess being formed at the outer end of the boring 25 to accommodate the gear teeth 29. Suitably journaled in the plate 30 below the disk is a spindle 32 on the inner 95 end of which is fixed a gear pinion 33 meshing with the gear teeth 29 on the disk 27, the spindle having a knurled head 34 on its outer end whereby it may be rotated.

For operating the tumblers 21 a key 35 100 with a non-stepped bit 36 may be employed, which operates with a cam action on the wall of the aperture 24 in the tumbler, this aperture being so located and proportioned that when the bolt is locked, with the tumbler in its lowered position the key must be inserted with the bit 36 turned downwardly in order for the latter to enter the aperture 24, the upper wall of which is then close to the shank of the key. As will be apparent, 110 when the tumbler is in locked position with the lug 21' engaging in the notch 23, if the

disk 27 is not in a position with the key-hole 28 turned downwardly the key can not be inserted directly into the aperture 24 and difficulty will be experienced in opening 5 the lock. After the key, therefore, is withdrawn the head 34 is rotated to turn the disk 27 to a position with the key-hole 28 facing other than downwardly.

The bolt 17 may engage in a suitable 10 keeper 40 secured by screws 41 in the door jamb 42, the opening 43 in the keeper facing transversely of the door as will be understood.

In the modification shown in Fig. 5 the 15 construction is in general the same except for the operating of the tumbler bar. In this construction the groove 26 which accommodates the latter is extended downwardly to the bottom of the casing 10, and 20 the tumbler bar extends downwardly in the groove to a position flush with the bottom of the casing when in locked position, the bolt being released by pressing upward with the finger on the lower end of the tumbler 25 bar, it being understood that the casing 10 will not be sunk into the door in this construction.

Having thus described my invention, what 30 I claim as new and desire to protect by Letters Patent of the United States is as follows:

1. In a lock, a casing, a bolt slidable in said casing from side to side thereof, said bolt being longer than the width of the casing 35 and having a notch formed in one edge thereof, and a tumbler bar slidable in the casing at right angles to the bolt and having a part adapted to engage in said notch, said tumbler having a circular aperture formed 40 therein adapted to receive the bit of a key, and said casing presenting a key-hole registering with said aperture.

2. In a lock, a casing, a bolt slidable in said casing from side to side thereof, said

bolt being longer than the width of the casing 45 and having a notch formed in one edge thereof, and a tumbler bar slidable in the casing at right angles to the bolt and having a part adapted to engage in said notch, said tumbler having a circular aperture 50 formed therein and adapted to receive the bit of a key, and said casing presenting a boring of larger diameter than said aperture leading inwardly to the said tumbler in registry with the said aperture, and a key-hole disk rotatable in said boring. 55

3. In a lock, a casing, a bolt slidable in said casing from side to side thereof, said bolt being longer than the width of the casing and having a notch formed in one 60 edge thereof, and a tumbler bar slidable in the casing at right angles to the bolt and having a part adapted to engage in said notch, said tumbler having a circular aperture formed therein and adapted to receive 65 the bit of a key, and said casing presenting a boring of larger diameter than said aperture leading inwardly to the said tumbler in registry with the said aperture, and a key-hole disk rotatable in said boring, said disk 70 having gear teeth formed on its periphery, and a pinion meshing with said gear teeth and adapted for manual rotation to angularly adjust the key-hole in the said disk.

4. In a lock, a casing, a bolt slidable in 75 said casing from side to side thereof and having a notch in its upper edge and a widened groove in its outer face, a tumbler bar extending upwardly across the said bolt and being accommodated in said widened 80 groove, said tumbler bar having a hooked upper end adapted to engage in said notch, said tumbler bar having a widened lower end formed with a circular aperture adapted 85 to be engaged by the bit of a key.

In testimony whereof I have affixed my signature.

STANLY TANSKI.
